W. E. Beck Jr.
ATTORNEY

UNITED STATES PATENT OFFICE

MERRILL BENNETT, OF HILLSBORO, NEW HAMPSHIRE

CIGARETTE MOLD

Application filed April 18, 1929. Serial No. 356,048.

My invention relates to an attachment for tobacco receptacles and more particularly a cigarette mold.

It is an object of the invention to provide a cigarette mold for forming cigarettes which is detachably associated with a tobacco can or the like.

A further object of the invention is to provide a cigarette mold detachably associated with a tobacco can which will enable the purchaser of the tobacco to readily form cigarettes with the tobacco in the can in a more efficient manner than the method now employed.

Another object of the invention is to provide a device of the above-mentioned character, which is simple and durable in construction, reliable and efficient in use, and inexpensive to manufacture.

Other objects and advantages of the invention will be apparent during the course of the following description.

In the accompanying drawing, forming a part of this specification and in which like numerals are employed to designate like parts throughout the same,

Fig. 1, is a fragmentary front elevation of a tobacco can with my invention applied thereto,

Fig. 2, is a top plan view of the same,

Fig. 3, is an end view of the same,

Fig. 4, is a longitudinal sectional view of the same and,

Fig. 5, is a section taken on lines 5—5 of Fig. 4.

In the drawing wherein for the purpose of illustration, I have shown a preferred embodiment of my invention, the numeral 5 denotes a conventional type of tobacco can having the usual hinged cover 6, at its upper end.

Referring more particularly to my invention a longitudinal body or trough 7, of semi-circular shape in cross section is formed from suitable metal. The ends 8 of the trough are circular in shape and extend beyond the longitudinal marginal edges of the trough. The trough is substantially the same length as the cover 6 of the can and when applied to the can is inverted and placed on top of

the cover so that one of the ends 8 extends down over the end of the cover while the other end is inserted in the transverse slot 9 formed in the top of the cover adjacent one end.

The mold is detachably held in place by the lug 10 struck upwardly from the top of the cover adjacent the end of the cover, opposite to the end in which the slot 9 is formed. The lug is substantially rectangular in shape, the ends of the lug being beveled, as at 11, to provide projecting points 12, adapted to be resiliently engaged by the sides of the mold when the mold is placed over the lug.

In use, the mold may be readily removed from the cover of the tobacco can by applying a slight pressure to the end adjacent the lug. The cigarette paper is then placed in the trough and filled with tobacco and the edges of the paper sealed in the well known manner. Thus, it is seen that the mold enables the user to form a more perfect cigarette, as the tobacco can be more compactly packed without breaking the paper and the paper can be filled to the extreme ends.

It is to be understood that the form of my invention herewith shown and described is to be taken as a preferred example of the same and that certain changes in the shape, size and arrangement of the parts may be made without departing from the spirit of the invention or the scope of the subjoined claims.

Having thus described my invention, I claim:

1. In a device of the character described, the combination with a tobacco can, of a longitudinal trough adapted to be disposed on the cover of the can, and means integral with the cover detachably securing said trough thereto.

2. In a device of the character described, the combination with a tobacco can, of a longitudinal trough adapted to be disposed on the cover of the can, and a lug integral with the cover adapted to be resiliently engaged by the side of the trough.

3. In a device of the character described, the combination with a tobacco can having a cover provided with a transverse slot adja-

cent one end, of a trough adapted to be disposed on the cover having its ends projecting beyond the longitudinal marginal edges of the trough, one of said ends being adapted 5 to be inserted in said slot, and a lug struck up from the cover adapted to be resiliently engaged by the sides of said trough, releasably holding the trough on the cover.

In testimony whereof I affix my signature.

10 MERRILL BENNETT.
